UNITED STATES PATENT OFFICE.

ISADOR SCHWARTZ, OF NEW YORK, N. Y.

METHOD OF PRODUCING, PHOTOGRAPHING, AND PRESENTING A CROSS-WORD PUZZLE.

Application filed December 8, 1924. Serial No. 754,656.

To all whom it may concern:

Be it known that I, ISADOR SCHWARTZ, a citizen of the United States, and a resident of New York city, in the county of New York and State of New York, have invented certain new and useful Improvements in Methods of Producing, Photographing, and Presenting a Cross-Word Puzzle, of which the following is a specification.

10 This invention relates to improvements in motion picture projection, and it consists of the steps of the method herein described and claimed.

An object of the invention is to provide 15 a feature of intellectual entertainment in motion picture programs, the main purpose being to incite the keen interest of the audience in the particular matter projected upon the screen.

20 Another object of the invention consonant with the foregoing is to present or project a cross word puzzle upon the screen in animated form, the picture being a running account of the puzzle, including the presentation of problems and the answers thereto, the purpose being to keep the audience 25 guessing and amused.

Other objects and advantages appear in 30 the following specification, reference being had to the accompanying drawings, in which the views represent portions of a motion picture film showing the various steps of the method of presenting a cross word puzzle as follows:

35 Figure 1 illustrates the introduction to the puzzle.

Figure 2 shows the chart which next appears upon the screen.

40 Figure 3 shows the first legend that is made to appear.

Figure 4 shows how the first puzzle word is made to appear.

45 Figure 5 illustrates the function of the hand, suggesting to the audience those squares of the chart in which the answer to the puzzle word is to appear.

Figure 6 shows the entrance of the artist's 50 hand into the picture preparatory to inserting the answer word in the square previously designated.

Figure 7 is a continuation of Figure 6, illustrating how the word has been completed.

Figure 8 shows another step in which

another legend and puzzle are made to 55 appear.

Figure 9 again shows the use of the guide finger in pointing out the vertical squares in which the next answer is to appear.

Figure 10 shows the completion of the 60 answer word by the artist hand.

Figure 11 illustrates a substantial repetition of the acts of the guide finger in Figures 5 and 9, the particular pointing step here illustrated being preparatory to the 65 presentation of an abbreviated puzzle word.

Figure 12 illustrates the completion of the abbreviated puzzle word by the artist hand.

Figure 13 shows how said word dissolves.

Figure 14 illustrates the explanation of 70 the abbreviated puzzle word.

Figure 15 shows how the explanation dissolves.

Figure 16 illustrates the restoration of 75 the initial letters of said puzzle word.

Figure 17 is a view showing the use of a card with comments on the puzzle.

Figure 18 illustrates the use of an eraser.

Figure 19 illustrates the use of an eraser under another circumstance.

Figure 20 shows a correction as a result 80 of the occurrence in Figure 19.

One of the purposes of the invention is to present a particular motion picture in 85 such a manner as to produce a keen interest of the audience. The subject chosen for these purposes is a cross word puzzle, and the various stages and developments of the puzzle are presented in such a way as to continually keep the audience guessing and 90 amused.

The drawings illustrate sections of a long film F, the film being of sufficient length to 95 allow for an adequate showing, of all of the various features of the cross word puzzle. The manner in which the puzzle is developed is as follows:

Figure 1 shows a frame 1 in which is printed the subject 2 of the film. This is supplemented by the name of the distributing agency, the photographer, possibly a patent notice, and such other information as is usually necessary to properly identify a film. The frame 1 is followed by a frame 3 in which is printed such descriptions and instructions as are necessary to prepare the audience for that which is to follow. The audience must know what part it is intended

to play in the entertainment and the printed matter in the frame 3 supplies the necessary information. It must be understood that frames 1 and 3 and subsequently appearing frames are repeated many times providing for a sufficiently long showing of the particular subject matter of the frames.

Figure 2 shows a frame 4 in which is printed a chart 5. The appearance of this chart is familiar to almost everyone. The chart is substantially square, and is ruled both horizontally and vertically to provide horizontal and vertical rows of squares.

The principle of a cross word puzzle is to produce such an arrangement of letters that words are readable in both directions. This general scheme is followed with but one exception as appears in connection with Figures 12 to 16. Only the horizontal rows 15 of squares 6 and 7 and the vertical row 8 are mentioned in this description, although in practice all of the rows will be used. The upper horizontal row 6 has eight white squares, the first of these containing an index numeral which in this case is "1".

Figure 3 shows the next step in the development of the puzzle. The legend 10 "Horizontal" in this case, appears at the left and in continuation of the upper row 6. For this and other purposes the chart 5 is set offcenter in respect to the frame 4 so that a considerable space 11 is left. It is in this space that the legend "Horizontal" appears. The audience is thus informed 30 that the first puzzle word will demand an answer word to be placed in one of the horizontal rows of squares.

Figure 4 shows the next step in which the puzzle word 12 is shown in the space 11. The word selected is "philanthropist". This word is surrounded by an outline 13 having an offset 14 at one end including an exponent numeral 15. In this case the exponent is "1", agreeing with the corresponding index numeral in the horizontal row 6.

Figure 5 shows how the index finger 16 of a hand 17 enters the frame 4, first pointing to the exponent numeral 15 and then to the successive squares in the horizontal row 6, suggesting to the audience that the answer word must fit in the eight squares thus designated. The audience is now set to guessing, and presently the solution of the first question begins.

Figure 6 illustrates this. The hand 18 of an artist, bearing a brush or pencil 19 is shown entering the frame 4 from beneath. The arrow *a* merely designates the direction that the hand and pencil take, and does not appear on the actual picture. The pencil proceeds to the upper row 6.

In Figure 7 the pencil 19 is shown as having completed the answer word 20, which, in this case, is "landlord". This particular

answer word is intended as a mirth provoker because the popularly accepted notion of a landlord seems to be contrary to a philanthropist who is a promoter of benevolent projects.

Figure 8 shows the chart 5 supplemented by the legend "Vertical". The numeral 10 is common to both legends that appear being a continuation of the upper row 6 in the space 11. This legend apprises the audience of a change in working the puzzle. A change in the printing in the outline 13 also occurs. The puzzle writing 12 now reads "Topics of the day". The outline 13 may contain either a puzzle word or phrase. The exponent numeral 15 has also been changed to "8", agreeing with the index numeral "8" in the first square of the vertical row 8.

Figure 9 directs the attention of the audience to the first vertical row 8. The index finger 16 appears as before; pointing first to the exponent numeral 15 and then to the nine white squares of the first vertical row in succession. This suggests to the audience that the answer word must contain eight letters and fit in the first vertical row.

Figure 10 illustrates the artist's pencil 19 as having completed the answer word "income-tax." This, again, is intended as a humorous reference to a popular subject. By this time the interest and sense of humor of the average audience will have been aroused so that it is more or less prepared to accept that which follows. The other squares are filled in according to the foregoing procedure.

Figure 11 shows the step in Figures 3 and 4 as already having been completed. The outline 13 now contains the legend "The tenant's pipe dream". The index finger 16 is shown in the act of pointing from the exponent numeral 15 to the horizontal row 7. The six white squares in this row are counted out by the index finger, again suggesting to the audience that the answer word must there appear.

Figure 12 shows the artist's pencil 19 as having completed the answer word 21. This word "iounfr" is meaningless and is intended to arouse the curiosity of the audience. In Figure 13 the letters of the "word" are shown as dissolving and other letters in the act of appearing. The vertical cross lines are now left out of the row 11, providing a complete blank space for the answer word.

Figure 14 illustrates the explanation of "The tenant's pipe dream" and makes use of the so-called word as the initial letters of words in the phrase "I owe U nothing for rent." This again is calculated to strike the fancy of the audience, the answer being an absurd comment on an existing fact.

Figure 15 illustrates a repetition of the

act in Figure 13 but now the phrase in Figure 14 is shown as dissolving while the former initial letters of the so-called "word" 21 are beginning to reappear. In Figure 16 these letters are completely restored as in Figure 12.

Figures 17 to 20 introduce other novelties which add to the interest of the picture. Take, for example, the stage of development of the puzzle in Figure 7. The puzzle phrase is "The tenant's pipe dream." The artist's hand 18 now introduces into the picture a card 22 bearing the wording "I worked on this all night: now you try it." This card is so introduced as to partially obscure the chart 5, and after a brief period the hand and card are withdrawn, revealing the chart in Figure 11. The initial letters are printed in the row 7 in due time. The artist is supposed to have made a mistake in his definition of a "philanthropist," reverting to the stage of development in Figure 4. He finds the word "loanshark" as containing too many letters for the squares in the upper row 6, whereupon the hand 15 appears with an eraser 23 going through the motions of erasing the word. The word is made to disappear in consonance with the motions, after which the right word appears.

Figures 19 and 20 are along the lines of Figure 18. In writing out the answer word in one of the rows of squares the artist is supposed to have erroneously spelled the word "held" (Fig. 20) by writing it "hell." Having discovered the error the eraser 23 again appears, and by going through the proper motion erases the last letter of the word which is then correctly spelled as it appears in Figure 20.

The reader must bear in mind that the working out of the puzzle is a continuous performance, that is to say the motion picture is continuous, properly advancing from one stage to the next, giving the audience the impression of actually participating in the working out of a cross word puzzle. By making use of the card 22, as in Figure 17, the artist talks to the audience as near as may be. While it is a common thing to work puzzles, particularly cross word puzzles, on paper and with pencil it is believed to be entirely new to photograph the steps of working out such puzzle, as well as the various acts incidental thereto as herein described and projecting the picture upon a screen for the education and entertainment of an audience.

I claim:—

1. The method of presenting a cross word puzzle by animated pictures consisting of the progressive steps of exhibiting a chart of predetermined configuration ruled in rows of predetermined configurations having index numerals, causing a legend to appear

outside of the chart directing attention to one of the rows, causing a puzzle writing to appear together with an exponent numeral relating to a row having a corresponding index numeral, picturing an index finger as pointing out first the exponent numeral, then the index numeral and the succeeding squares in said row suggesting the number of letters of the answer, picturing a hand with a marking implement in the act of filling the letters of an enigmatical word in the squares previously pointed out, causing the dissolving of said word, causing the gradual and finally the full appearance of an explanation of said enigmatical word. 80

2. The method of presenting a cross word puzzle by animated pictures consisting of the progressive steps of exhibiting a chart ruled in horizontal and vertical rows of squares having index numerals, causing a legend to appear beside the chart directing attention to one or the other kind of rows, causing a puzzle writing to appear beneath said legend together with an exponent numeral relating to a row having a corresponding index numeral, picturing an index finger as pointing out first the exponent numeral, then the index numeral and the succeeding squares in said row suggesting the number of letters of the answer, picturing a hand with a marking implement in the act of filling the letters of an enigmatical word in the squares previously pointed out, causing the dissolving of said word, causing the gradual and finally the full appearance of an explanation of said enigmatical word, 95

100

3. The method of presenting a cross word puzzle by motion picture projection consisting of the progressive, photographically pictured steps of exhibiting a chart ruled in horizontal and vertical rows of squares having index numerals, causing a legend to appear beside the chart directing attention to one or the other kind of rows, causing a puzzle writing to appear beside the chart together with an exponent numeral relating to a row having a corresponding index numeral, picturing an index finger as pointing out first the exponent numeral then the index numeral and the succeeding squares in said row suggesting the number of letters of the answer, picturing a hand with a marking implement in the act of filling initial letters in the squares previously pointed out, thus constituting a meaningless word, causing said letters to dissolve and the cross ruling in said rows to disappear, causing the gradual and finally full appearance of an explanatory clause in the blank space thus provided employing words of which the former letters are initials, causing the 115

120

125

130

dissolving of said explanation, and causing the complete restoration of the former initial letters.

4. The method of presenting a cross word puzzle by motion picture projection consisting of the progressive, photographically pictured steps of exhibiting a permanent chart ruled in horizontal and vertical rows of squares having index numerals, causing a legend to appear beside the chart directing attention to one or the other kind of rows, causing a puzzle writing to appear beside the chart together with an exponent numeral relating to a row having a corresponding index numeral, picturing a card as moving over the face of the chart partially obstructing the view of the chart and containing a remark concerning the puzzle writing, withdrawing the card to again reveal the chart and proceeding with the solving of the puzzle writing.

5. The method of presenting a cross word puzzle by animated pictures consisting of the progressive steps of exhibiting a chart of predetermined configuration containing figures having predetermined shapes, said figures having index numerals, causing a legend to appear outside of the chart directing attention to said pictures, causing a puzzle writing to appear together with an exponent numeral relating to a picture having a corresponding index numeral, picturing an index finger as pointing out first the exponent numeral, then the index numeral and the figure in which the answer is to appear, picturing a hand filling in an enigmatical word, causing the dissolving of said word, and causing the appearance of a translation of said word in substitution thereof.

ISADOR SCHWARTZ.
